United States Patent Office

Des. 207,401

Patented Apr. 11, 1967

207,401

DYNAMOELECTRIC MACHINE

Loren E. Andrews, Fort Wayne, Ind., Frederick W. Baumann, Scotia, N.Y., George B. Dunn, Jr., Fort Wayne, Ind., and Roger B. Kerr, Topsfield, Mass., assignors to General Electric Company, a corporation of New York

Filed June 30, 1965, Ser. No. 85,967

Term of patent 14 years

(Cl. D26—5)

FIG. 1

FIG. 2

FIG. 3.

FIG. 4.

FIGURE 1 is a perspective view illustrating the front and side portions of a dynamoelectric machine embodying the new design;

FIGURE 2 is a perspective view similar to FIGURE 1 and illustrating the back and side portions of the machine;

FIGURE 3 is a top view of the article of FIGURE 1; and

FIGURE 4 is a bottom view of the article of FIGURE 1.

We claim:

The ornamental design for a dynamoelectric machine, as shown.
